BOAT CONSTRUCTION AND CONTROL OF
SAILS

Louis Sveinsson, Baltimore, Md.

Application September 20, 1950, Serial No. 185,809

1 Claim. (Cl. 114—39)

1

This invention relates to improvements in sail boats.

An object of the invention is the provision of a housing built into the bottom of a boat and containing a mechanism for not only rockably supporting a mast but for limiting rocking movement of the mast which controls the position of the tiller in accordance with the wind pressure on a sail of the boat, said housing projecting into the water, being impervious to water, and functioning as a buoyant force for the boat while acting as a centerboard because of its streamlined shape.

Another object of the invention is the provision of a relatively narrow and elongated housing sealed to the bottom of a boat and opening at its upper end into the bottom of the boat with the sidewalls of the housing curving inwardly towards each other and terminating at the bottom in a common thin edge to form a center board, said housing functioning as a pontoon adjacent the bow of the boat, the mast of the boat being supported by a step pivoted at its lower end on a shaft borne by the housing so that the step and mast may rock transversely of the boat, arms crossing each other, having the lower ends pivoted on opposite sidewalls of the housing with the upper ends cushioned by springs supported by brackets pivoted on the underside of the deck, linkage connecting the lower end of the step at opposite sides thereof, with the lower ends of the arms to limit rocking movement of the mast and to provide a plurality of forces for aiding in maintaining stabilization of the boat.

A further object of the invention is the provision of a watertight housing secured to the bottom of a sail boat and disposed longitudinally along a portion of the keel for exerting a buoyant force on the boat adjacent the bow and functioning as a center board, a plurality of instrumentalities connected between the housing, the underside of the deck and a mast-supporting step pivoted in the housing for limiting rocking movement of the mast and for creating forces which will eliminate substantially any ballast.

This invention is best understood from a consideration of the following detailed description taken in connection with the accompanying drawings, nevertheless, it must be borne in mind that the invention is not limited to the disclosure but is susceptible of such changes and modifications as shall define no material departure from the salient features of the invention as expressed in the appended claim.

2

In the drawings:

Figure 1 is a transverse vertical section of a sail boat taken along the line 1—1 of Figure 2 showing the particular improvements therein;

5 Figure 2 is a longitudinal vertical section of the boat taken along the line 2—2 of Figure 1;

Figure 3 is a fragmentary horizontal section taken along the line 3—3 of Figure 1;

10 Figure 4 shows more or less diagrammatically a front end view and a plan view of the boat riding along a straight line indicating the course tendency of the symmetrical plan of the bottom of the boat; and

15 Figure 5 shows more or less diagrammatically a front end view and a plan view of the boat tending to move off its course, the shading indicating the unsymmetrical plan of the bottom of the boat.

Referring more particularly to the drawings 10
20 designates a sailboat having a fin 11 and a rudder 12 which is operated by a tiller 13 through a shaft 14 mounted for rocking movement in the stern of the boat. A mast 15 is mounted in a step generally designated by the numeral 16. An opening 17 in the deck 18 of the boat permits rocking of the mast transversely of the boat.

25 A housing 20 has a peripheral flange 21 received by an elongated opening 22 in the bottom 23 of the boat. An annular metal rim 24 is bolted at 25 to the flange 21 while the rim 24 is wide enough to project over the periphery of the opening for supporting the housing from the bottom of the boat. The housing has a hollow portion 26 and a solid tapered portion 27 which acts as a center board.

30 The framing or mast step 16 has an elongated bottom portion running lengthwise of the axis of the boat which is in the form of an elongated sleeve 30 for receiving an axle 31 mounted at the ends thereof in bearings 32 formed in upper ends of the housing diametrically opposite points and just below the rim 24. The mast step is substantially triangular in shape and has a socket 33 at the apex thereof for receiving a lower reduced portion 34 of the mast 15. The reduction 45 of said end of the mast forms a shoulder which rests upon the upper end of said socket.

Ears 35 rigid with the bottom of the step 16 project in opposite directions from the step. A link 36 is pivoted at one end to each ear. A second link 37 has one end pivoted to the other end of each first mentioned link. The other end of each second mentioned link is pivoted to the adjacently disposed lower end of a curved arm 38 or 39.

The arm 38 has the lower end pivoted in a saddle or pedestal 40 secured to the curved inner face of one sidewall of the housing 20. The arm 39 has its lower end pivoted in a saddle 41 on the opposite wall of the housing. These arms cross each other above the axle 31 and pass through the open spaces in the mast step 16. The upper free end of each arm at opposite sides of the step have pivotal connections at 42 with an adjacently disposed bolt 43 which passes through an opening in a flange 44 on the lower end of a bracket 45. A coil spring 46 is received by the bolt and has one end resting on a hemispherical washer 47 which is supported by a curved seat in the flange 44. A washer 48 and a nut 49 on the upper end of each bolt not only retains the spring in place but also provides means for adjusting the tension on the springs. The upper ends of the brackets 45 are hinged on plates 50 which are bolted to the under face of the deck 18 at opposite sides of the opening 17 in the deck 18. The mast 15 has a forked crosstree 51 (Figure 1) at the lower end thereof adjacent the deck 18 of the boat. A plurality of guy wires 52 connected to the top of the mast extend downwardly and are received by passages in the ends of the arms of the crosstree. The lower ends of said wires are connected to turnbuckles 53 which in turn are attached to rings 54 secured to the upper end 33 of the step 16. Other guy wires 55 are also connected between the top of the mast and the turnbuckles. These wires stabilize the mast.

Cables 56 and 57 have an end attached at 58 to the free end of the tiller 13 and after being trained on a pulley 59 extend forwardly towards the bow of the boat. The cable 56 is trained on a pulley 60 mounted in a bracket which is secured to the deck and the free end of said cable is attached to a ring 61 rigid with the lower end of the mast just below the crosstree 51. The cable 57 is trained on a pulley 62 carried by a bracket which is bolted to the deck 18 at a point diametrically opposite the pulley 60. The free end of the cable is attached to a ring 63 fixed to the mast at a point diametrically opposite the ring 61.

A boom 65 is attached to the mast 15 (Figures 4 and 5) in the usual manner. A sail (not shown) is secured between the boom and the mast in a well known manner.

The housing 20 is watertight and is sealed to the boat also in a watertight manner. Said housing acts as a midship pontoon thereby providing an upward buoyant force for aiding in producing in effect a lightweight boat so that said boat will glide freely over the surface of the water. The pontoon effect aids the boat in stepping up out of the water in contradistinction to the usual sailboat which must be ballasted to sink deep into the water so that such crafts must plow through the water.

Arrows are applied to Figures 1, 4 and 5 to illustrate more clearly the operation of my improvements when applied to a sailboat. In Figure 1, arrow *a* indicates the direction of the force of the wind while arrow *b* shows the direction of the buoyant force on the bottom of the boat. These two forces act at right angles to each other. Arrows *c* disclose the direction of the leverage applied by the force of the wind over the axle 31 of the mast step 16 through the medium of the links 36 and 37 and the attached elements.

Arrow *d* indicates the downward force which in effect represents the ballast, and, in this par-

ticular case, weight elimination. On the other hand, arrow *e* points out more directly the upward pull on the pedestals 40 and 41 when the mast is rocked in a vertical plane disposed transversely of the boat.

In the plan views in Figures 4 and 5, arrows *f* and *f'* illustrate respectively the straight course of the boat under normal conditions and a course the boat tends to take under abnormal conditions. In Figure 5, the tendency of the boat to turn towards the weather side is corrected by instrumentalities which are brought into play by the oscillation of the mast and the mast step on the axle or shaft 31 in a manner which will be described presently.

When the wind force acts on the mast 15 in the direction represented by the arrow *a* (Figures 1 and 5) said mast through the medium of the sail will tilt towards the lee side of the boat while the boat is also tilted exposing a greater area of the bottom of the boat as indicated by the unshaded portion in the plan view in Figure 5. However, the tilting of the mast causes a similar angular movement of the step so that the rope or cable 56 will exert a pull on the tiller which in turn will rock the rudder 12 to the position shown in Figure 5 for steering the boat on its true course. When the wind force on the sail and mast tilts said mast in the opposite direction from that indicated by the arrows in Figures 1 and 5, the rope 57 will cause the tiller to move the rudder in the opposite direction for maintaining the boat on its course.

When the mast is vertically disposed all of the parts in the body of the boat and in the housing 20 are in balance. When the mast 15 is tilted in the direction indicated by the dotted lines in Figure 5 (end view) and the arrows *a* in Figures 1 and 5, the links 36 and 37 connected between the ear 35 and the pedestal 40 will exert a downward pressure on the arm 38 and on said pedestal. The arm in turn will exert a pull on the spring 48 at the right hand side in Figure 1 while pressure will be relieved on the other spring 46. This action will tend to draw the weather side of the boat down in the water. If the mast is tilted in the opposite direction, the elements just described will reverse their positions and with an opposite effect.

Numerous functions may be attributed to the housing 20 beside being a watertight enclosure for the links 36, 37 and the lower ends of the step 16 and the arms 38 and 39. The streamlined shape of the housing as shown in Figures 1 and 2 performs the function of a center board. Said housing gives a buoyant effect to the boat since it acts as a midship pontoon, whereby the boat may glide freely over the water.

The mechanism in the boat and housing (Figures 1 and 2) when brought into play by the tilting of the mast 15 and step 16 tends to eliminate the necessity of providing ballast since the forces are in counterbalance. Thus, one force cannot become dominant.

What I claim:

In a sailboat having a mast, a deck and a bottom, the deck and bottom adjacent the bow being provided with an opening, a watertight housing depending from the bottom and having the upper end opening into the space between the deck and bottom, means attaching the open end of the housing to said body, curved arms located below the opening in the deck and crossing each other above the opening in the housing, means pivotally mounting the lower ends of the arms on the

opposite inner side walls of the housing, a shaft mounted in bearings in the housing and disposed longitudinally of the boat, a step pivoted on the shaft and provided with a socket projecting through the deck opening, the heel of the mast received by the socket, spring means pivoted to the underface of the deck and having pivotal connections with the adjacently disposed upper ends of the arms and linkage at each side of the step and having pivotal connections between the 10 lower end of the step and an adjacently disposed lower end of an arm, the arms, linkage and springs limiting rocking movement of the step and mast.
